[57] CLAIM

The ornamental design for a 4-in-1 remote control unit, as shown.

DESCRIPTION

FIG. 1 is a perspective view of a 4-in-1 remote control unit, from the front and above;

FIG. 2 is a top plan view of the 4-in-1 remote control unit;

FIG. 3 is a bottom plan view of the 4-in-1 remote control unit;

FIG. 4 is a right side elevational view of the 4-in-1 remote control unit;

FIG. 5 is a left side elevational view of the 4-in-1 remote control unit;

FIG. 6 is a front elevational view of the 4-in-1 remote control unit; and,

FIG. 7 is a rear elevational view of the 4-in-1 remote control unit.
